UNITED STATES PATENT OFFICE

128,814

DESIGN FOR AN UMBRELLA RACK

Clara N. Wells, Evanston, Ill.

Application May 28, 1941, Serial No. 101,206

Term of patent 7 years

To all whom it may concern:

Be it known that I, Clara N. Wells, a citizen of the United States, residing in Evanston, in the county of Cook and State of Illinois, have invented a new, original, and ornamental Design for Umbrella Racks, of which the following is a specification, reference being had to the accompanying drawing, forming part thereof.

In the drawing:

Fig. 1 is a front perspective view of an umbrella rack, showing my design;

Fig. 2 is a front elevational view;
Fig. 3 is a side elevational view thereof; and
Fig. 4 is a cross-sectional view, taken on the line 4—4 of Fig. 2 and in the direction of the arrows.

I claim:

The ornamental design for an umbrella rack, as shown.

CLARA N. WELLS.
